UNITED STATES PATENT OFFICE.

ALFRED H. HUMPHREY, OF KALAMAZOO, MICHIGAN.

DESIGN FOR A GAS-LAMP.

SPECIFICATION forming part of Design No. 36,861, dated March 29, 1904.

Application filed December 17, 1901. Serial No. 86,816. Term of patent 7 years.

To all whom it may concern:

Be it known that I, ALFRED H. HUMPHREY, a citizen of the United States, residing at the city of Kalamazoo, in the county of Kalamazoo and

5 State of Michigan, have invented a new, original, and ornamental Design for Gas-Lamps, of which the following is a specification.

My new, original, and ornamental design for a gas-lamp is shown in the accompanying drawing, which is a perspective view thereof.

What I claim as new, and desire to secure by Letters Patent, is—

The ornamental design for a gas-lamp substantially as shown.

ALFRED H. HUMPHREY. [L. S.]
